CARRIER SYSTEM

George W. Halstead, Jr., Columbus, Ohio, assignor to General Electric Company, a corporation of New York

Application July 26, 1932. Serial No. 624,741

12 Claims. (Cl. 212—132)

My invention relates to carrier systems where-
in a carrier is adapted to be set in operation, as
for example at a loading station, and there-
after travel to another station, such as an un-
5 loading station, where it is automatically re-
versed and brought back to the loading station.

More specifically, my invention provides im-
proved accuracy in the control of traveling buck-
et storage equipments of the type operated by
10 means of a single cable which serves both for the
hoisting and for the horizontal travel of the
bucket or carrier. Each end of the cable is
wound about a hoisting drum while a loop in the
cable, suitably supported from pulleys, serves
15 for the support of a bucket or material carrier.
The drums are, therefore, rotated in the same
direction during the raising or lowering of the
bucket. The horizontal travel of the bucket is
accomplished by connecting a trolley motor by
20 means of a clutch to one of the hoisting drums
and through a differential to the other hoisting
drum so that the trolley motor drives the drum
in opposite directions.

If the single cable drive is to be operated auto-
25 matically both hoisting and trolley limit switches
are necessary to control the energization of the
respective motors. The hoisting limit switch can
be directly connected to the hoisting motor. If
the trolley limit switch is connected directly to
30 the trolley motor, however, any slippage what-
ever of the clutch causes inaccuracies in the
stopping of the bucket. Inasmuch as this slip-
page is accumulative, it will be seen that after a
35 number of operations the bucket might be
brought to a standstill some distance from the
unloading station.

In carrying out my invention in one form
thereof, I provide means responsive only to op-
posite movements of the hoisting drums for oper-
40 ating a trolley limit switch. More specifically, I
provide a second differential the bevel gears of
which are respectively arranged to be driven from
the hoisting drums, so that when the hoisting
drums are rotated in the same direction the bevel
45 gears are rotated in opposite directions. Con-
sequently, by gearing the trolley limit switch to
the ring gear of the differential this switch is
not operated during the hoisting operations, but
as soon as the drums rotate in opposite direc-
50 tions the bevel gears are rotated in the same di-
rection thereby causing the ring gear to operate
the trolley limit switch in direct proportion to
the horizontal travel of the bucket.

For a more complete understanding of my in-
55 vention, reference should now be had to the

drawings in which Fig. 1 illustrates diagrammati-
cally my invention applied to a material carry-
ing system; Fig. 2 is a perspective view, partly in
section, of an adjustable limit switch used for
the selection of a particular silo which is to be 60
filled, while Fig. 3 diagrammatically illustrates
a suitable control system as applied to the ap-
paratus shown in Fig. 1.

Referring now to Fig. 1, I have shown my in-
vention in one form as applied to the control of 65
a hoisting motor 10 and of a trolley motor 11,
which motors serve to drive a material carrying
bucket 12 through a predetermined cycle of op-
erations. The bucket 12 is supported by a loop
13 in a supporting cable 14. By means of the 70
cable 14 the bucket is raised and lowered as well
as moved in a horizontal direction. It will be ob-
served that one end of the cable is wound about
a hoisting drum 15, the cable extending from the
drum over pulley 16, round pulley 17, over the 75
pulley 18 supported in a carriage 20 and to the
bucket 12. The other end of the cable is wound
about a hoisting drum 21 and extends from the
drum over a pulley 22, about a pulley 23, and
over a pulley 24 supported from the carriage 20 80
to the bucket 12. The carriage 20 is supported
from a track or I-beam 25 which track extends
over the silos or unloading stations 1L, 1R and
2R. A loading station, commonly called the pit,
is indicated at 26.

It will be observed that the hoisting motor 10,
by means of a bevel gear 30, is geared to a ring 85
gear 31 of a differential mechanism 32. The
hoisting drum 15 is connected by means of the
shaft 33 to the bevel gear 34 of the differential 90
mechanism while the shaft 35 serves to connect
the hoisting drum 21 to the bevel gear 36 of the
differential. The hoist limit switch 38 is geared
to the hoisting motor 10 and serves, as a part of 95
its function, to control the energization of the
hoisting motor. An electrically operated clutch
40 serves to connect and disconnect the trolley
motor 11 from the hoisting drum 21. As shown,
this clutch is in its disengaged position and if the
hoisting motor 10 is energized it will be seen that 100
the hoisting drums 15 and 21 are rotated in the
same direction, so that the cable 14 is either
wound on the drums, thereby causing the loop
13 to shorten and the bucket 12 to raise, or the
cable may be unwound, thereby lengthening the 105
loop 13 and causing the bucket 12 to be lowered.

Assuming that the bucket 12 is in the position
shown and it is desired to move the bucket to
the left, the clutch 40 is operated to connect the 110

trolley motor 11 to the drum 21 and this motor is energized in a direction to rotate the drum 21 in a direction to unwind the cable therefrom. At the same time the drum 15 is driven in a direction to wind up the cable inasmuch as the direction of rotation of the trolley motor 11 is reversed by means of the differential 32.

The trolley limit switch 42, which serves as a part of its function to control the energization 10 of the trolley motor 11, is geared to the drums 15 and 21 by means of a differential mechanism 43. Inasmuch as the trolley limit switch is to be operated whenever the bucket moves in a horizontal direction, the bevel gears 44 and 45 are arranged 15 to be driven in opposite directions whenever the hoisting drums 15 and 21 are rotating in the same direction. This is accomplished by directly connecting the bevel gear 44 by means of a sprocket gear 46, a sprocket chain 47, and a sprocket gear 20 48 secured to the shaft 33. The bevel gear 45 is driven by means of a sprocket gear 49 secured to the shaft 35, sprocket chain 50, a sprocket gear 51, and by gears 52 and 53. The provision of the gears 52 and the gear 53 secured to the bevel 25 gear 45 causes the bevel gear to be rotated in one direction whenever the bevel gear 44 is rotated in the opposite direction. As soon, however, as drums 15 and 21 are rotated in opposite directions, it will be observed that the bevel gears 44 and 30 45 are rotated in the same direction thereby imparting rotation to the ring gear 55 of the differential mechanism 43, and by means of the gear 56 the operation of the trolley limit switch is accomplished.

35 As I have stated, if the trolley limit switch had been connected to the trolley motor any slippage of the clutch would have introduced an error in bringing the bucket 12 to a standstill. By connecting the trolley limit switch through a differential, however, inaccuracies of stopping have 40 been substantially, if not entirely, eliminated.

Referring now to Fig. 2, I have shown one form 45 of a limit switch which is suitable for the selection of the desired silo, as well as for the control of the energization of the trolley motor. This limit switch forms no part of the present invention. It is fully described and broadly claimed in application Serial No. 588,368, filed January 23, 1932 by Clyde H. Freese, entitled "Carrier system" and 50 assigned to the same assignee as the present invention and which application also describes and claims a control system for carriers. I therefore do not herein claim anything shown or described in said Freese application which is to be regarded 55 as prior art with respect to this present application. Briefly, this limit switch may be described in the present application by stating that the trolley limit switch 42 consists of six lug carrying disks 61, 62, 63, 64, 65 and 66. Each disk, as for example 60 the disk 61, is provided with holes 67 distributed about its periphery so that the lugs 68, 69 and 70 secured thereto may be adjusted to any desired angular position. The lug 68 serves to close contacts 71 whenever this lug engages the small 65 metal wheel 72 carried on the lower part of the armature 73 of the switch 71. A compression spring 74 normally urges the contacts 71 to their open position. As the lug 68 engages the wheel 72, however, the armature 73 is rotated about the 70 shaft 76 and the contact 71 are latched into their closed position by means of a member 77 pivotally carried by shaft 78. The member 77 is biased upwardly by compression spring 79 so that as soon as the contacts 71 are closed the member 77 engages 75 the notched lower end 80 of the armature

73. The contacts may be opened by the lug 69 or the lug 70 engaging a wheel 82 carried by the member 77. The result of the lug striking the wheel 82 is to cause the member 77 to be pushed out of engagement with the lower end 80 so that the compression spring 74 opens the contacts. It will be understood, of course, that the remaining contacts are similarly opened and operated.

The selection of a silo into which coal or like material is to be carried is accomplished by the adjustment of the relative angular positions of the disks 61, 62 and 63 with respect to the disks 64, 65 and 66. The latter disks serve to stop the trolley motor of the bucket whenever it reaches the position over the loading station while the loading contacts serve to stop the bucket over a selected silo. These contacts 64, 65 and 66 are driven by bevel gear 56 while the adjustable contacts 61, 62 and 63 are driven by the meshing gears 84, 85, 86 and 87. Independent rotation 90 of the gears 85 and 86 is accomplished by the movement of wedge 88 secured to a rod 89 away from a housing 90, to which rod and housing are respectively secured the gears 85 and 86. An outwardly flaring flange 91 of the housing 90 provides a convenient means of rotating the housing and in conjunction with a pointer 92 forms an indicating disk which may be calibrated for the respective silos. For example, the indicator 92, as shown, points to 2L meaning the second 105 left-hand silo. If the wedge 88 were released and the flange 91 rotated until 1R occupied a position opposite the indicator 92, the selection of the first right-hand silo would have been accomplished.

The hoisting limit switch 38 is provided with a 110 plurality of normally open and normally closed contacts of the same general design as the trolley limit switch 42.

It is believed that a thorough understanding of the arrangement and operation of the various 115 parts of a suitable control system will best be understood from a complete description of the operation of the system as a whole and, therefore, the construction and arrangement of certain typical devices only will be first described in detail. 120 As shown in Fig. 3, the hoisting motor 10 and the trolley motor 11 are of the alternating current type. The direction of rotation of the hoisting motor 10 is controlled by means of the direction switches 98 and 99, while the direction switches 125 100 and 101 control the direction of rotation of the trolley motor 11. A slack cable switch 102 is arranged to open a pair of contacts 103 and to close a pair of contacts 104 whenever the bucket 12 comes into engagement with the material with- 130 in a selected silo. A plurality of sequence relays 105, 106, 107, 108 and 109 of the latched-in type provide positive interlocking of the circuits so that the cycle of operations may be maintained irrespective of power failure. These switches are 135 similarly constructed; for example, the switch 105 is arranged to be latched into position by means of a member 110 engaging a shoulder 111 provided on the armature of the sequence relay 105. A trip coil 112 is arranged to release the 140 latching member 110 from engagement with the shoulder 111 so that the relay 105 may be operated to its unlatched position. A timing relay 113 is provided with a time delay device 114 so that the time of closing of this relay may be ad- 145 justed as desired. Additional timing relays 115 and 116 are respectively provided with short circuited windings 117 and 118 which serve to introduce a time interval before these relays close their contacts.

It is now believed that a comprehensive understanding of the invention, including the construction and arrangement of the various apparatus, as well as its operation, will be facilitated by a description of the operation of the system as a whole.

In the operation of my invention in the form shown it will be assumed that the bucket 12 has been lowered to the loading station or pit 26 and it is desired to drive the bucket 12 continuously from the loading station to and from the first right-hand silo or unloading station. Consequently, the wedge 88 is moved away from the housing 90 until the flange 91 is rotated into the position which brings the indicia 1R into coincidence with the pointer 92. The line switches L1 and L2 are then closed to energize the supply lines 120 and 121. An energizing circuit may be immediately traced from the supply line 120 for the operating coil 122 of the sequence relay 106. This circuit may be traced from supply line 120 by conductor 123, contacts 124 of the sequence relay 105, conductors 125 and 126, contacts 127 of the sequence relay 107, conductors 128 and 129, non-adjustable trolley limit switch contacts 64, conductor 130, operating coil 122 and by conductors 131 and 132 to the other supply line 121. The sequence relay 106 will thereupon be operated to its latched-in position with its contacts 133 and 134 and 135 closed, and its contacts 136, 137 and 138 opened. As soon as the contacts 133 are closed the time relay 113 is energized through a circuit which may be traced from the supply line 120 by conductor 123, contacts 124 of the sequence relay 105, conductor 140, hoisting limit switch contacts 141, contacts 133 of the sequence relay 106, operating coil 142 of the timing relay 113 and by conductor 132 to the other supply line 121. At the same time the sequence relay 108 is operated to its latched-in position by reason of an energizing circuit which may be traced from the supply line 120 by conductor 123, contacts 124 of sequence relay 105, conductor 140, hoisting limit switch contacts 141, contacts 133 of sequence relay 106, conductor 144, operating coil 145 of the sequence relay 108 and by conductors 146 and 147 to the other supply line 121.

The timing relay 113 by reason of the timing device 114 does not immediately close its contacts and by thus introducing a time interval permits the loading of the bucket 12 with coal or the like before it is hoisted from the loading station. As soon as this relay closes its contacts, however, the sequence relay 107 is operated into its latched-in position by reason of an energizing circuit which may be traced from the supply line 120 by conductor 123, contacts 124 of the sequence relay 105, conductor 140, hoisting limit switch contacts 141, contacts 133 of the sequence relay 106, conductor 144, contacts 150 of the timing relay 113, operating coil 151 of the sequence relay 107 and by conductors 152 and 132 to the other supply line 121.

The closing of the contacts 154 of the sequence relay 107 serves to energize the hoisting direction switch 98 of the hoisting motor 10 through a circuit which may be traced from the supply line 120, by conductor 123, contacts 124 of sequence relay 105, conductor 125, hoisting limit switch contacts 155, conductor 156, contacts 154 of the sequence relay 107, conductor 157, operating coil of the hoisting relay 98, interlock contacts 160 of lower direction switch 99 and by conductor 161 to the other supply line 121.

Consequent to the closing of the hoisting direc-

tion switch 98, the hoisting motor 10 is energized in a direction to rotate drums 15 and 21 so as to wind the cable onto these drums thereby hoisting the bucket 12 from the loading station 26.

The hoisting relay 115 is operated to open its contacts 162 and 163 as soon as the hoisting direction switch 98 closes by reason of the closing of the contacts 164 operated with this direction switch. This circuit may be traced from the supply line 120 by conductor 165, operating coil of the hoisting relay 115, conductor 166, contacts 164 and by conductor 167 to the other supply line 121. The function of the hoisting relay 115 is to introduce a time interval before the trolley motion of the bucket can be initiated.

As soon as the bucket 12 reaches the trolleying position above the silos the hoisting limit switch contacts 141 and 155 are operated to their open positions while the hoisting limit switch contacts 170 and 171 are closed. The hoisting direction switch 98 is thereby deenergized so that the bucket 12 immediately comes to a standstill. The contacts 164 of the hoisting direction switch 98 are opened to interrupt the energizing circuit of the hoisting relay 115, which relay closes after a predetermined interval. The hoisting limit switch contacts 170 partially complete an energizing circuit for the sequence relay 105. This circuit is completed as soon as the hoisting relay 115 closes its contacts 163. Assuming that the time interval has expired and that the contacts 163 are closed, the energizing circuit for the sequence relay 105 may be traced from the supply line 120 by conductor 172, hoisting limit switch contacts 170, conductor 173, operating coil 174 of the sequence relay 105, conductor 175, contacts 176 of the sequence relay 107, conductor 178, contacts 163 of the timing relay 115 and by conductor 177 to the other supply line 121. The sequence relay 105 is thereupon operated to its latched-in position with its contacts 124 and 178 open and its contacts 179, 180 and 181 closed.

The opening of the contacts 178 of the sequence relay 105 reenergizes the clutch releasing coil 185, while the contacts 179 of the relay 105 completes an energizing circuit for the clutch engaging coil 186. This energizing circuit may be traced from the supply line 120 by conductor 187, contacts 179 of the sequence relay 105, conductor 188, the clutch engaging coil 186 and by conductors 189 and 190 to the other supply line 121. The clutch 40 is thereby operated to connect the trolley motor 11 to the hoisting drum 21.

Inasmuch as the bucket is to be driven to the right-hand silo, the switch 191 is operated to its right-hand position. The direction switch 101 of the trolley motor 11 is now closed, so that the trolley motor is energized in a direction to drive the bucket towards the right-hand silo, by means of an energizing circuit which may be traced from the supply line 120 by conductor 172, hoisting limit switch contacts 170, conductor 173, contacts 180 of the switch relay 105, adjustable trolley limit switch contacts 63, contacts 192 of the sequence relay 108, conductor 193, contacts 194 of sequence relay 109, conductor 195, reversing switch 191, conductor 196, operating coil of the direction switch 101 and by conductor 197 to the other supply line 121.

The time closing relay 115 is energized to open its contacts 162 and 163 by reason of the closing of the contacts 198 operated with the direction switch 101. The energized circuit completed may be traced from the supply line 120, by conductor 165, operating coil of the relay 115, conductors 150

166 and 199, contacts 198 of the direction switch 101 and by conductor 200 to the other supply line 121.

As soon as the bucket 12 reaches the position 5 over the first right-hand silo 1R the trolley limit switch contacts 63 are operated to their open position while the trolley limit switch contacts 61, 62 and 66 are closed. The opening of the contacts 63 serves to deenergize the direction switch 101 which immediately opens and the trolley motor 11 is brought to a standstill with the bucket 12 in position for lowering into the silo. At the same time the contacts 198 are opened to deenergize the time closing relay 115. The closing 10 of the trolley limit switch contacts 62 completes an energizing circuit for the trip coil 202 of the sequence relay 107. This circuit may be traced from the supply line 120 by conductor 203, trolley limit switch contacts 62, conductor 203', contacts 204 of the sequence relay 108, conductor 205, contacts 206 of the sequence relay 107, trip coil 202 and by conductor 147 to the other supply line 121. The sequence relay 107 is, therefore, operated to its unlatched position to close its contacts 207 thereby completing energizing circuit 25 for the trip coil 208 of the sequence relay 108. This circuit may be traced from the supply line 120 by conductor 203, trolley limit switch contacts 62, conductor 203', contacts 204 of the sequence relay 108, conductors 205 and 209, trip coil 208, contacts 210 of the sequence relay 108, conductor 211, contacts 207 of the sequence relay 107 and by conductor 147 to the other supply line 121.

35 It will be assumed that the time closing relay 115 has closed its contacts 162 and 163. An energizing circuit for the trip coil 112 of the sequence relay 105 may now be traced from the supply line 120 by conductor 172, hoisting limit switch contacts 170, conductor 173, contacts 181 of the sequence relay 105, trip coil 112, conductor 215, contacts 216 of the sequence relay 107, contacts 162 of the hoisting relay 115 and by conductors 217 and 177 to the other supply line 121. 40 The sequence relay 105 is immediately operated to its unlatched position, thereby interrupting by means of its contacts 179 the circuit to the clutch engaging coil 186 while the clutch releasing coil 185 is energized through the contacts 178 operated with the sequence relay 105. The clutch 45 40 is thereupon operated to disengage the trolley motor from the hoisting drum 21. The contacts 124 of the sequence relay 105 are closed as this relay is unlatched and completes an energizing 50 circuit for the trip coil 218 of the sequence relay 106. This circuit may be traced from the supply line 120 by conductor 123, contacts 124 of the sequence relay 105, conductors 125 and 126, contacts 127 of the sequence relay 107, conductors 55 60 128 and 219, trolley limit switch contacts 61, conductor 220, contacts 134 of the sequence relay 106, trip coil 218 and by conductors 221 and 132 to the other supply line 121.

As soon as this relay 106 is unlatched the equipment 65 is in readiness for the bucket 12 to be lowered into the silo. An energizing circuit may be traced for the lower-direction switch 99 of the hoisting motor 10 from the supply line 120 by conductor 123, contacts 124 of the sequence relay 70 105, conductors 125 and 126, contacts 127 of the sequence relay 107, conductors 128 and 216, contacts 137 of the sequence relay 106, conductor 217, contacts 103 of the slack cable switch 102, conductor 217', operating coil of the lowering direction switch 99 and by conductor 217'' to the

other supply line 121. The hoisting motor 10 is thereupon energized in a direction to lower the bucket 12 into the silo. As the bucket descends into the silo the hoisting limit switch contacts 155 are closed.

80

As soon as the bucket strikes the coal or other material which is being carried to the silo, the tension is removed from the supporting cable and the slack cable switch 102 operates to open its contacts 103 and to close its contacts 104. Of course, the lowering direction switch 99 is immediately deenergized as soon as the contacts 85 103 are opened and the hoisting circuits are established by the closing of the slack cable switch contacts 104 which contacts complete energizing circuits for the sequence relays 107 and 109.

85

The energizing circuit for the sequence relay 109 may be traced from the supply line 120 by conductor 123, contacts 124 of the sequence relay 105, conductors 125, 225, contacts 138 of the sequence relay 106, conductor 226, contacts 104 of the slack cable limit switch 102, conductor 227, operating coil 228 of the sequence relay 109 and by conductors 229, 230 and 132 to the other supply line 121.

90

The energizing circuit for the sequence relay 107 is derived from the conductor 227 forming a part of the energizing circuit for the sequence relay 109 and may be traced from the conductor 227 by conductor 231, contacts 136 of the sequence relay 106, conductor 232, operating coil 151 of the sequence relay 107 and by conductors 152 and 132 to the other supply line 121.

95

These sequence relays are immediately operated to their latched-in positions. Consequently the energizing circuit may now be traced for the operating coil of the hoisting direction switch 98 from the supply line 120 by conductor 123, contacts 124 of the sequence relay 105, conductor 125, hoisting limit switch contacts 155, conductor 156, contacts 154 of the sequence relay 107, conductor 100 155, operating coil of the hoisting direction switch, contacts 160 of the lowering direction switch 99 and by conductor 161 to the other supply line 121.

100

Consequent to the closing of the hoisting direction switch 98, the hoisting motor 10 is energized in a direction to hoist the carrier or bucket 12 from the silo 1R. The closing of the contacts 164 operated with the hoisting direction switch again serves to complete the energizing circuit for the time closing relay 115 which relay 110 immediately opens its contacts.

105

As the bucket reaches its trolleying position above the silos the hoisting limit switch contacts 155 are opened to deenergize the hoisting direction switch 98. The hoisting limit switch contacts 141 are also opened while the hoisting limit switch contacts 170 and 171 are closed.

110

The time closing relay 115 after a predetermined time interval closes its contacts 163 to complete an energizing circuit for the operating coil 174 115 of the sequence relay 105. This sequence relay is immediately operated to its latched-in position to complete the energizing circuit for the clutch engaging coil 186.

115

The closing of the contacts 180 of this sequence relay completes an energizing circuit for the operating coil of the direction switch 100, which circuit may be traced from the supply line 120 by conductor 172, hoisting limit switch contacts 170, conductor 173, contacts 180, trolley limit switch contacts 66, conductor 235, contacts 236 of the sequence relay 108, conductor 237, contacts 238 of the sequence relay 109, conductor 239, reversing switch 191, conductor 240, and 240', operating coil of the direction switch 100 and by conductor 241 to the

120

125

As the bucket reaches its trolleying position above the silos the hoisting limit switch contacts 155 are opened to deenergize the hoisting direction switch 98. The hoisting limit switch contacts 141 are also opened while the hoisting limit switch contacts 170 and 171 are closed.

130

The time closing relay 115 after a predetermined time interval closes its contacts 163 to complete an energizing circuit for the operating coil 174 135 of the sequence relay 105. This sequence relay is immediately operated to its latched-in position to complete the energizing circuit for the clutch engaging coil 186.

135

The closing of the contacts 180 of this sequence relay completes an energizing circuit for the operating coil of the direction switch 100, which circuit may be traced from the supply line 120 by conductor 172, hoisting limit switch contacts 170, conductor 173, contacts 180, trolley limit switch contacts 66, conductor 235, contacts 236 of the sequence relay 108, conductor 237, contacts 238 of the sequence relay 109, conductor 239, reversing switch 191, conductor 240, and 240', operating coil of the direction switch 100 and by conductor 241 to the

140

145

As the bucket reaches its trolleying position above the silos the hoisting limit switch contacts 155 are opened to deenergize the hoisting direction switch 98. The hoisting limit switch contacts 141 are also opened while the hoisting limit switch contacts 170 and 171 are closed.

140

The time closing relay 115 after a predetermined time interval closes its contacts 163 to complete an energizing circuit for the operating coil 174 145 of the sequence relay 105. This sequence relay is immediately operated to its latched-in position to complete the energizing circuit for the clutch engaging coil 186.

145

The closing of the contacts 180 of this sequence relay completes an energizing circuit for the operating coil of the direction switch 100, which circuit may be traced from the supply line 120 by conductor 172, hoisting limit switch contacts 170, conductor 173, contacts 180, trolley limit switch contacts 66, conductor 235, contacts 236 of the sequence relay 108, conductor 237, contacts 238 of the sequence relay 109, conductor 239, reversing switch 191, conductor 240, and 240', operating coil of the direction switch 100 and by conductor 241 to the

150

other supply line 121. As soon as this direction switch is closed the trolley motor 11 is energized in a direction to drive the bucket to the loading station while the contacts 242 operated with this direction switch complete an energizing circuit for the time closing relay 115.

The bucket 12 is brought to a standstill over the loading station by the opening of the trolley limit switch contacts 66 which deenergize the direction switch 100. At the same time the trolley limit switch contacts 64 and 65 are operated to their closed positions. The closing of the trolley limit switch contacts 65 completes an energizing circuit for the trip coil 202 of the sequence relay 107. This circuit may be traced from the supply line 120 by conductor 243, trolley limit switch contacts 65, conductor 244, contacts 245 of the sequence relay 108, conductors 209 and 205, contacts 206 of the sequence relay 107, trip coil 202 and by conductor 147 to the other supply line 121. The sequence relay 109 is also operated to its unlatched position by reason of the completion of an energizing circuit for its trip coil 248, which circuit may be traced from the supply line 120 by conductor 243, trolley limit switch contacts 65, conductors 244 and 249, contacts 250 of the sequence relay 109, trip coil 248 and by conductor 251 to the other supply line 121.

As soon as the time closing relay 115 closes its contacts the energizing circuit for the trip coil 112 is completed and the sequence relay 105 is thereby operated to its unlatched position. The sequence relay 106 is now operated into its latched-in position by the energizing circuit traced above with this relay. Consequently, an energizing circuit is now completed for the time closing relay 116 which circuit may be traced from the supply line 120 by conductor 123, contacts 124 of the sequence relay 105, conductors 125 and 40 126, contacts 127 of the sequence relay 107, conductor 128, hoisting limit switch contacts 171, contacts 135 of the sequence relay 106, conductor 254, operating coil 255 of the relay 116 and by conductors 230 and 132 to the other supply line 121. The interval required for the closing of this relay is introduced in order to give the bucket time to come to a standstill and to eliminate the swinging of the bucket before it is lowered to the loading station. As soon as this relay 116 closes the energizing circuit is completed for the lowering direction switch 99, which circuit is derived from the conductor 254, forming a part of the energizing circuit for the operating coil of the relay 116, by conductor 257, contacts of the time closing relay 116, conductors 258 and 217', operating coil of the lowering direction switch 99 and by conductor 217'' to the other supply line 121. The hoisting motor 10 thereby rotates in a direction to lower the bucket to the loading station. The bucket or carrier is brought to a standstill by the opening of the hoisting limit switch contacts 171 which interrupts the energizing circuit to the lowering direction switch 99. At the same time the hoisting limit switch contacts 170 are opened while the contacts 141 and 155 are closed.

A complete cycle of operation has now been described and it will, of course, be understood that the carrier may be continuously operated from the loading station to a selected unloading station, and my invention insures the accurate stopping of the bucket 12 above the loading station or a selected site irrespective of any slippage of the clutch in the trolley motor of the hoisting drum.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. In combination, a pair of hoisting drums, a trolley motor arranged to drive said drums in opposite directions, a hoisting motor for rotating said drums in the same direction, a trolley limit switch for controlling the energization of said trolley motor, and means responsive to the opposite rotation of said drums for operating said limit switch. 80 85

2. In combination a traction drive, a cable for supporting and driving a carrier, a pair of drums around which the ends of said cable are wound, a differential mechanism mechanically connecting said drums, a hoisting motor mechanically connected to said differential mechanism for simultaneously rotating said drums in forward or reverse direction, a trolley motor arranged to drive said drums in opposite directions, a limit switch for controlling the energization of one of said motors, and means responsive only to opposite movements of said drums for operating said limit switch. 90 95

3. A material handling system having a carrier arranged to be operated in a predetermined cycle from a loading station to and from an unloading station comprising a single cable for supporting and imparting translational movement to said carrier, traction drums around which the ends of the cable are wound, a differential mechanism mechanically connecting said traction drums, a hoisting motor arranged to drive through said differential mechanism said drums in the same directions, a trolley motor arranged to be mechanically connected to one of said traction drums for rotating said end drums in opposite directions, a trolley limit switch, a second differential mechanism connected to said limit switch and interposed between said limit switch and said traction drums, and driving connections for said second differential mechanism responsive to the rotation of said drums in opposite directions for causing said second differential to operate said limit switch. 100 105 110 115

4. A material handling system having a carrier arranged to be operated in a predetermined cycle from a loading station to and from one of a plurality of unloading stations, means for driving said carrier including a pair of cable drums, a trolley limit switch having a plurality of non-adjustable switches for stopping said carrier over said loading station and a plurality of adjustable switches for stopping said carrier over an unloading station, means for changing the time of operation of said latter switches with respect to said former switches so that any one of said unloading stations may be selected for the carrying out of said cycle, and means responsive to the opposite rotation of said drums for operating said limit switch. 120 125 130 135

5. An electrically operated carrier system having a carrier arranged to be operated in a predetermined cycle between a loading station and a plurality of unloading stations, a cable for supporting and driving said carrier, a pair of drums around which the ends of said cable are wound, a hoisting motor for selectively driving said drums in the same direction, a trolley motor 140 145 150

- for driving said drums in opposite directions, hoisting and trolley limit switches for controlling the energization of said motors, and means responsive to the opposite rotation of said drums 5 for operating said trolley limit switch.
6. An electrically operated carrier system having a carrier arranged to be operated in a pre-determined cycle between a loading station and a plurality of unloading stations, a cable for supporting and driving said carrier, a pair of drums around which the ends of said cable are wound, a hoisting motor for simultaneously rotating said drums in forward or reverse direction, a trolley motor for driving one drum in one direction 10 while driving the other drum in the other direction, a trolley limit switch, a clutch for disengaging said trolley motor from said drums, and means responsive to the rotation of said drums in opposite directions for operating said 15 limit switch.
7. An electrically operated carrier system having a carrier arranged to be operated in a pre-determined cycle from a loading station to and from an unloading station, a cable for supporting and imparting translational movement to said carrier, a pair of traction drums around which the ends of the cable are wound, a differential mechanism mechanically connecting said drums, a hoisting motor for driving said 20 drums through said differential mechanism in forward and reverse directions, a trolley motor for driving said drums in opposite directions, a clutch for connecting said trolley motor to one of said end drums, hoisting and trolley limit 25 switches each of which is provided with a plurality of contacts, means responsive to the rotation of said drums in opposite directions for operating said trolley limit switch, and a plurality of control circuits successively completed 30 by said switches, the completion of each of said control circuits being dependent upon the control circuit last established and upon the operation of said switches.
- 40 8. A material handling system comprising a pair of drums, motive means for rotating said
- drums in the same directions, a second motive means for rotating said drums in opposite directions, means for controlling said second motive means and means responsive to the opposite rotation of said drums for operating said motive 80 means controlling means.
9. A material handling system comprising a pair of drums, a differential coupling said drums, a motor for driving said drums in opposite directions, a second motor for driving said drums in the same directions, a limit switch for controlling said first motor, and a differential means for operating said limit switch responsive to opposite rotations of said drums. 85
10. A material handling system comprising a carriage, a track for said carriage, a pair of drums, cable means connecting said drums with said carriage, a trolley, a motor for rotating said drums in opposite directions, a limit switch for said motor and differential means for operating said limit switch responsive to the position of said carriage on the track. 90
11. A conveyor system comprising at least one loading station and a plurality of unloading stations, a carriage, driving means for said carriage, 100 material supporting structure, motive means for hoisting and lowering said structure toward and away from said carriage, a second motive means for moving said carriage between said loading station and a selected one of said unloading stations and a differential mechanism for controlling said second motive means, responsive to the 105 location of said carriage.
12. A conveyor system comprising at least one loading station and a plurality of unloading stations, a carriage, an electric motor for driving said carriage, material supporting structure, a second electric motor for hoisting and lowering said structure toward and away from said carriage, a limit switch for said first motor and a 110 differential means responsive to a predetermined position of said carriage for operating said limit switch. 115

- for driving said drums in opposite directions, hoisting and trolley limit switches for controlling the energization of said motors, and means responsive to the opposite rotation of said drums 5 for operating said trolley limit switch.
6. An electrically operated carrier system having a carrier arranged to be operated in a pre-determined cycle between a loading station and a plurality of unloading stations, a cable for supporting and driving said carrier, a pair of drums around which the ends of said cable are wound, a hoisting motor for simultaneously rotating said drums in forward or reverse direction, a trolley motor for driving one drum in one direction 10 while driving the other drum in the other direction, a trolley limit switch, a clutch for disengaging said trolley motor from said drums, and means responsive to the rotation of said drums in opposite directions for operating said 15 limit switch.
7. An electrically operated carrier system having a carrier arranged to be operated in a pre-determined cycle from a loading station to and from an unloading station, a cable for supporting and imparting translational movement to said carrier, a pair of traction drums around which the ends of the cable are wound, a differential mechanism mechanically connecting said drums, a hoisting motor for driving said 20 drums through said differential mechanism in forward and reverse directions, a trolley motor for driving said drums in opposite directions, a clutch for connecting said trolley motor to one of said end drums, hoisting and trolley limit 25 switches each of which is provided with a plurality of contacts, means responsive to the rotation of said drums in opposite directions for operating said trolley limit switch, and a plurality of control circuits successively completed 30 by said switches, the completion of each of said control circuits being dependent upon the control circuit last established and upon the operation of said switches.
- 40 8. A material handling system comprising a pair of drums, motive means for rotating said
- drums in the same directions, a second motive means for rotating said drums in opposite directions, means for controlling said second motive means and means responsive to the opposite rotation of said drums for operating said motive 80 means controlling means.
9. A material handling system comprising a pair of drums, a differential coupling said drums, a motor for driving said drums in opposite directions, a second motor for driving said drums in the same directions, a limit switch for controlling said first motor, and a differential means for operating said limit switch responsive to opposite rotations of said drums. 85
10. A material handling system comprising a carriage, a track for said carriage, a pair of drums, cable means connecting said drums with said carriage, a trolley, a motor for rotating said drums in opposite directions, a limit switch for said motor and differential means for operating said limit switch responsive to the position of said carriage on the track. 90
11. A conveyor system comprising at least one loading station and a plurality of unloading stations, a carriage, driving means for said carriage, 100 material supporting structure, motive means for hoisting and lowering said structure toward and away from said carriage, a second motive means for moving said carriage between said loading station and a selected one of said unloading stations and a differential mechanism for controlling said second motive means, responsive to the 105 location of said carriage.
12. A conveyor system comprising at least one loading station and a plurality of unloading stations, a carriage, an electric motor for driving said carriage, material supporting structure, a second electric motor for hoisting and lowering said structure toward and away from said carriage, a limit switch for said first motor and a 110 differential means responsive to a predetermined position of said carriage for operating said limit switch. 115
